Ino. J. Rathbone of Albany N. Y.
Letters Patent No. 292. Dated June 18, 1850.

The Schedule referred to in these Letters Patent and making part of the same.

To whom it may concern:

Be it Known that I, John J. Rathbone
of the City of Albany, and State of New York, have produced a new Ornamental Design for a
Cooking Stove (which Stove is known as the Queen of the West) and I do hereby declare that
the annexed and accompanying drawings are a full & accurate delineation of the ornamental parts, with their
several ornaments of the said Stove.

Dec. 28th

What I claim as my production and desire to secure by Letters Patent is the combination and arrangement of Ornamental figures and forms represented in the accompanying Drawings, forming together an ornamental design for a Cooking Stove.

Witnesses,

Richrd Varick De Witt
J. B. Brinsmade Jr.
